BEADLIKE METAL SURFACE ORNAMENTATION

Otto Paul Riedel, Bergenfield, N. J., assignor to
Metaphane, Inc., a corporation of New York

Application December 23, 1937, Serial No. 181,402

10 Claims. (Cl. 41—24)

This invention relates to a composite wall covering producing raised bead-like metal effects.

An object of this invention is to provide a composite wall covering having ornamental figures thereon which are made by closely spaced points in relief pressed out on the entire surface of the ornamental figures and out of the normal plane of the said wall covering.

Another object of this invention is to provide a composite wall covering comprising a sheet of paper having a layer of metal foil on one of its faces and having simulations of linear outlines of ornamental figures pressed out on the paper face and extending into the metal foil face and lying in relief on the metal face, and by covering the ornamental areas with clear lacquer and the spaces around the simulated outlines in relief with a layer of coloring matter contrasting with the color of the metal foil and producing at least a two-tone color effect.

In my prior patent application, Serial No. 165,440, I have disclosed a composite wall covering simulating inlaid metal effects which were made by scoring the outlines of the ornamental figures in relief. The scored outlines of the figures were very distinct and outstanding. In the present disclosure I produce ornamental figures which scintillate all over the area of the figures by means of raised bead-like metal effects.

I subdue the luster of the metallic figured portions by applying thereto a layer of colored and substantially transparent lacquer.

I apply a layer of coloring matter all around the ornamental figures, the coloring matter being of a different color than the lacquered metal. I have thus produced a practical wall covering which is ornamented with esthetic figures in at least two-tone color effect and which may be positively and permanently attached to a wall by applying paste all over the normally concealed paper surface of the wall covering so that the entire sheet of wall covering including the ornamental figured areas is positively attached to the wall.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a fragmentary plan view of a com-

posite wall covering having a conventional ornamental metallic figure thereon which is made by closely spaced bead-like points in relief pressed out on the surface of the ornamental figure and out of the normal plane of the said wall covering, a portion of the figure being plain.

Figure 2 is an enlarged cross-sectional view, the section being taken as on line 2—2 in Figure 1.

Figure 3 is a fragmentary plan view of a composite wall covering having an ornamental metallic figure, a portion of which is covered with colored lacquer.

Figure 4 is an enlarged cross-sectional view, the section being taken as on line 4—4 in Figure 3.

Figure 5 is a fragmentary plan view of a modified composite wall covering showing an ornamental metallic figure having a bead-like pointed outline and dash-like impressions over the surface of the figure.

Figure 6 is a fragmentary plan view of a modified composite wall covering showing a conventional leaf metallic figure having a point-by-point broken outline and having interior point-by-point impressions simulating portions of the ribs of a leaf, portions of the figure being covered with variously colored lacquers.

Figure 7 is a fragmentary plan view of a modified composite wall covering having pointed bead-like impressions all over the entire area of the wall covering, portions of the surface area being covered with a layer of coloring matter forming a ground and having other portions uncovered and exposing metallic figures having a softened lustrous effect.

Figure 8 is a cross-sectional view, the section being taken as on line 8—8 in Figure 7.

Figure 9 is a fragmentary plan view of a modified wall covering having bead-like impressions over the entire area around the ornamental figures, the figured metallic areas being plain but having a subdued metallic effect.

Figure 10 is a cross-sectional view, the section being taken as on line 10—10 in Figure 9.

Figure 11 is a fragmentary plan view of a modified wall covering having a plain metallic surface on the entire area around the ornamental figures, the figured areas being ornamented with colored lacquer through which the metal shines faintly.

Figure 12 is a cross-sectional view, the section being taken as on line 12—12 in Figure 11.

In the illustrated embodiment of the invention shown in Figures 1 and 2, the numeral 10 indicates a composite wall covering producing raised bead-like metal effects and adapted to be pasted

to a wall and comprising a sheet of flexible paper 11 having an integral layer of metal foil 12 on one of its faces.

As shown in Figures 1 and 2, the composite wall covering 10 has a point-by-point bead-like broken outline 13 made by pointed impressions 16 forming an ornamental metallic figure 14. The point-by-point outline of the ornamental figure 14 has been impressed on the paper face and extends into the metal foil face and lies in relief on the metal face.

The interior of the ornamental figure 14 has been fabricated with closely spaced pointed bead-like impressions 16 in relief leaving a central portion plain, as shown by the numeral 12. The space around the figure or around the broken outline in relief has been covered with a relatively flexible covering or coating 15 contrasting in color with the metal foil so as to produce a two-tone color effect. The coating 15 extends to the broken outline 13 and lies below the upper surface of the broken outline. The pointed bead-like impressions 16 are of very small diameter and of small surface area so that paste can enter therein and when the composite wall covering 10 is pasted to a wall, the entire normally concealed surface of said wall covering has paste applied to it.

Figure 3 shows a modification of the wall covering shown in Figure 1. This wall covering identified by the numeral 17 comprises a sheet of flexible paper 18 having an integral layer of metal foil 19 on one of its faces. The composite wall covering 17 has a point-by-point bead-like broken outline 20 made by pointed impressions 21 forming an ornamental figure 22. The point-by-point outline of the ornamental figure has been impressed on the paper face and extends into the metal foil face and lies in relief on the metal face. The space around the figure or around the broken outline in relief has been covered with a relatively flexible covering or coating 23 contrasting in color with the metal foil so as to produce a two-tone color effect. The coating 23 extends to the broken outline 20 and lies below the upper surface of the broken outline. The pointed bead-like impressions 21 are of very small diameter and of small surface area so that paste can enter therein and when the wall covering is pasted to a wall practically the entire normally concealed paper surface has paste applied to it.

Figure 3 shows a portion of the ornamental figure 22 covered with substantially transparent colored lacquer 24. The portion 24 is made darker than the portion 21 to subdue the metallic luster of the foil.

Figure 5 shows a modification of the wall coverings shown in Figures 1 to 4, inclusive. The wall covering identified by the numeral 25 comprises a sheet of flexible paper (not shown) having an integral layer of metal foil 26 on one of its faces. The composite wall covering 25 has a point-by-point bead-like broken outline 27 forming an ornamental metallic figure 28. The surface of the figure 28 has fabricated therein raised dash-like impressions 29. The space around the figure or around the broken outline has been covered with a relatively flexible covering or coating 30 contrasting in color with the metal foil so as to produce at least a two-tone color effect. The point-by-point outline and dash-like impressions break up and soften the metallic finish.

Figure 6 shows a modified wall covering 35 comprising a sheet of flexible paper (not shown)

and having an integral layer of metal foil 36 on one of its faces. The composite wall covering 35 has a point-by-point bead-like broken outline 31 forming an ornamental leaf metallic figure 38. The leaf portions have point-by-point raised impressions simulating lines or ribs 39. The surface of the figure 38 has a colored portion 40 made by superposing a layer of substantially transparent colored lacquer through which the metallic surface underneath shines through and brightens the colored lacquer surface. The figure 36 has another portion 41 covered with a layer of colored and substantially transparent lacquer darker than the portion 40 through which the metallic surface reflects but faintly. The variously colored layers of lacquer subdue and darken the metallic sheen of the metal foil 36 and the ornamental metallic figure acquires a refined and highly valued finish which the original metal foil does not possess.

Figure 7 shows a modified wall covering 45 comprising a sheet of flexible paper 46 having an integral layer of metal foil 47 on one of its faces. The composite wall covering 45 has pointed bead-like raised impressions 48 all over the entire area 25 of the wall covering. Portions of the metal surface area are covered and concealed with a layer of coloring matter 49 forming a dull ground. Another portion is uncovered and exposes a metallic figure 50 having a broken surface and a 30 subdued metallic effect.

I have found by experiment that the paper backing has to have sufficient body to act as a reinforcement for the thin metal foil, but only of such thickness as will permit the composite 35 wall or surface covering to be rollable. The paper backing must also be adapted for glueing to a wall.

It is to be noted that the colored flexible covering forming a ground around the ornamental 40 figures is substantially "flat" and forms a dull surface without gloss.

Figures 9 and 10 show a modified wall covering 55 comprising a sheet of flexible paper 56 having integrally secured thereto a thin sheet of 45 metal or metal foil 57. The composite wall covering 55 has bead-like impressions 58 over the entire area around the ornamental figures. The figured metallic areas 59 are plain or without the bead-like impressions but have a subdued metallic effect. The bead-like impressions 58 are covered with a relatively flexible coating 60 forming a dull ground.

Figures 11 and 12 show a modified wall covering 61 comprising a sheet of flexible paper 62 55 having integrally secured thereto a thin sheet of metal or metal foil 63. The composite wall covering 61 has a plain metallic surface on the entire area around the ornamental figures. The figured metallic areas 64 may be ornamented 60 with contrasting colored lacquer 65 and 66 through which the metal shines faintly. The areas around the metallic figures 64 is covered with a relatively flexible coating 67 forming a dull ground.

It is to be noted that my composite metallic wall covering prevents light and air from passing through. My metallic wall covering deprives insects of the necessities for existence and prevents their germination and thriving.

It is also to be noted that the wall covering herein disclosed is non-porous and will not allow any moisture to pass through the ornamental figured metallic portions or through the colored paint ground.

In comparison with wall paper heretofore known, it is to be noted that the wall papers now in use are porous and have a tendency to absorb moisture and retain disease germs. My composite non-porous metallic wall covering has non-porous surfaces which will not absorb moisture or retain disease germs.

It is to be noted that the flat figured portion of the metallic foil surface may be broken up and made less pronounced, to produce a subdued metallic effect, as shown at 21 in Figure 3, or that a coating of colored and substantially transparent lacquer may be applied to portions of the figures, as shown at 40 and 41 in Figure 6, to 15 subdue the luster.

In accordance with the patent statutes I have described and illustrated the preferred embodiments of my invention, but it will be understood that various changes and modifications can be 20 made therein without departing from the spirit of the invention as defined by the appended claims.

I may fabricate and break up the ornamental surface areas otherwise than by bead-like or by 25 dash-like impressions in relief.

I claim:

1. A composite non-porous metallic wall paper having raised scintillating metal figures, comprising a sheet of paper having a layer of metal 30 foil on one of its faces, said sheet having bead-like portions in the form of scintillating ornamental figures impressed on the paper face, said bead-like impressions extending into the metal foil face and lying in relief on said metal face, 35 at least a portion of said bead-like figures being covered with colored and substantially transparent lacquer and causing said figures to have a subdued metallic luster, portions of said metal foil surface outside said bead-like figures in relief being covered with a non-glossy and flexible 40 layer of opaque coloring matter contrasting with and concealing the metal foil, said bead-like impressions being at least on the outlines of the figures, said metallic wall paper being rollable, each of said bead-like impressions being of small 45 area to permit positive attachment of the entire sheet of said metallic wall paper to a wall by pasting all over said paper face and including said impressed 50 figures in relief.

50 2. A composite wall covering producing raised scintillating metal effects, comprising a sheet of paper having a layer of metal foil on one of its faces, said sheet having bead-like portions in the form of scintillating ornamental figures 55 impressed on the paper face, said bead-like impressions extending into the metal foil face and lying in relief on said metal face, at least a portion of said bead-like figures being covered with transparent lacquer, portions of said metallic 60 layer outside said bead-like figures in relief being covered with a layer of opaque coloring matter contrasting with and concealing the metal foil, said bead-like impressions being at least on the outlines of the figures, said metallic wall paper being rollable, each of said bead-like impressions being of small area to permit positive attachment of the entire sheet of said metallic 65 wall paper to a wall by pasting all over said paper face and including said impressed figures in relief.

70 3. A composite wall covering producing raised scintillating metal effects, comprising a sheet of paper having a layer of metal foil on one of its faces, said sheet having bead-like portions in 75

the form of scintillating ornamental figures impressed on the paper face, said bead-like impressions extending into the metal foil face and lying in relief on said metal face, said bead-like figures being covered with colored transparent lacquer, 5 portions of said metallic layer outside said bead-like figures in relief being covered with a layer of opaque coloring matter contrasting with and concealing the metal foil, said bead-like impressions being at least on the outlines of the figures, 10 said metallic wall paper being rollable, each of said bead-like impressions being of small area to permit positive attachment of the entire sheet of said metallic wall paper to a wall by pasting all over said paper face and including 15 said impressed figures in relief.

4. A composite wall covering comprising a sheet of paper having a layer of metal foil on one of its faces, said sheet having pointed bead-like 20 figures on the paper face, said bead-like impressions extending into the metal foil face and lying in relief all over the areas of the figures on said metal face, portions of said metallic layer outside said bead-like figures in relief being covered with 25 a layer of opaque coloring matter forming a dull ground contrasting with and concealing the metal foil, said bead-like impressions being at least on the outlines of the figures, said metallic wall paper being rollable, each of said bead-like impressions being of small area to permit positive attachment of the entire sheet of said metallic wall paper to a wall by pasting all over said paper face and including said impressed figures in 30 relief.

5. A composite non-porous wall covering having ornamental metallic figures comprising a sheet of paper having a layer of metal foil on one of its faces, said sheet having pointed bead-like 40 impressions on the paper face, said bead-like impressions extending into the metal foil face and lying in relief and in closely spaced relation on said metal face, said impressions forming ornamental figures on said metal face, said bead-like figures being covered with substantially 45 transparent lacquer, portions of said metallic layer outside said bead-like figures in relief being covered with a flexible layer of opaque coloring matter contrasting with and concealing the metal foil, said bead-like impressions being at least on 50 the outlines of the figures, said metallic wall paper being rollable, each of said bead-like impressions being of small area to permit positive attachment of the entire sheet of said metallic wall paper to a wall by pasting all over said paper face 55 and including said impressed figures in relief.

6. The invention as defined in claim 4 wherein portions of the said ornamental metallic figures are without any impressions to form a contrast 60 within each figure.

7. A composite wall covering comprising a sheet of paper having a layer of lustrous metal foil on one of its faces, said sheet having pointed bead-like 65 impressions on the paper face, said bead-like impressions extending into the metal foil face and lying in relief all over the metal face, portions of said metal face being covered with a layer of opaque coloring matter forming a ground, other portions of said metal face being uncovered and exposing metallic figures, said metallic figures having a broken surface, each of said bead-like impressions being of small area to permit positive attachment of the entire sheet of said metallic 70

wall paper to a wall by pasting all over said paper face.

8. A composite non-porous wall covering comprising a layer of paper and an integral superimposed metallic layer, said metallic layer having bead-like impressions and ornamental figures fabricated therein, portions of said metallic layer outside the ornamental figures being covered with a non-glossy and flexible layer of opaque coloring matter concealing said metallic layer and forming a dull ground, portions of said ornamental figures being covered with substantially transparent colored lacquer producing metallic figures having a subdued metallic luster, said metallic wall covering being rollable, each of said bead-like impressions being of small area to permit positive attachment of said wall covering to a wall by pasting all over said paper layer.

9. A composite non-porous wall covering comprising a layer of paper and an integral superimposed metallic layer, said metallic layer having bead-like impressions and ornamental figures fabricated therein, portions of said metallic layer outside the ornamental figures being covered with

a non-glossy and flexible layer of opaque coloring matter concealing said metallic layer and forming a dull ground, and means for subduing the metallic effect of said figures, said metallic wall covering being rollable, each of said bead-like 5 impressions being of small area to permit positive attachment of said wall covering to a wall by pasting all over said paper layer.

10. A composite non-porous metallic wall paper, comprising a layer of paper and an integral 10 superimposed lustrous metallic layer, portions of said metallic layer being covered with and concealed by a flexible layer of opaque coloring matter forming a dull ground, portions of said metallic surface being uncovered and exposing ornamental metallic figures, a layer of transparent coloring material upon said exposed metallic figures, said transparent coloring material being adapted to subdue said metallic luster whereby said figures appear in a darkened metallic sheen, 15 said metallic wall paper being rollable and adapted for positive attachment to a wall by pasting all over said paper layer.

OTTO PAUL RIEDEL.
